JET-TYPE BURNER FOR TOBACCO CURERS

Henry A. Oldenkamp, Valhalla, N. Y., assignor to American Machine and Foundry Company, a corporation of New Jersey

Application March 17, 1951, Serial No. 216,180

5 Claims. (Cl. 158—28)

This invention relates to jet type burners and more particularly to improvements in the type of burner shown in my copending application Serial Number 179,710 filed August 16, 1950, now Patent No. 2,673,726, dated March 30, 1954.

It has been found that a burner such as is disclosed in the above named application has a number of critical adjustments which must be accurately set. Any deviation from such a setting may result in incomplete combustion and as a consequence there may be accumulation of carbon in the burner which ultimately has a further deleterious effect on the combustion. Such incomplete combustion is objectionable in many cases because the incompletely combusted gases have a deleterious effect on the product being processed such as tobacco undergoing curing. It has also been noted that inexperienced individuals sometimes seek to make corrections to a jet type burner to overcome deficiencies which they may have thought existed, not realizing that the adjustments are extremely critical. As a result burners which were operating satisfactorily have been rendered unsatisfactory. In manufacturing and shipping burners of this type, it is also desirable to eliminate features of a burner which can be a source of trouble because of the burner being incorrectly assembled and adjusted.

It is an object of this invention to provide a burner of such construction that the adjustments are not readily interfered with, particularly those which are critical and which if not accurately maintained will cause fuel to be incompletely combusted.

A further object of this invention is to improve the design of the burner so as to eliminate contours and pockets which might tend to accumulate carbon and soot and cause undesirable turbulences in the combustion chamber.

A further object of this invention is to provide a nozzle holder with a support which will automatically locate the nozzle in the correct position for complete combustion.

Another object is to provide a jet type burner which will be of relatively simple design and which can be adapted for mass production.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Fig. 1 is a sectional plan view of the improved burner assembly.

Fig. 2 is a sectional end elevation of the same taken on line 2—2 of Fig. 1.

Fig. 3 is another sectional end elevation taken on line 3—3 of Figure 1.

Fig. 4 is an isometric view of the entire burner unit.

The apparatus I have employed to illustrate this invention consists of a combustion chamber made up of a cup-shaped cap 10, and a cylinder 12. The combustion chamber is surrounded by an outer conical shell 14 which in this illustration consists of two half shell sections 16 and 18 which make up the nose of the burner. The half shell sections 16 and 18 are made of special non-corroding and heat resisting material to prevent warping and facilitates having a smooth flowing air stream. The outer shell 14 is attached to and forms the nose of a suitably shaped duct 17 projecting from the fan housing 19 of

2

the burner unit illustrated in Fig. 4. Duct 17, like outer shell 14, consists of two half shells held together in a manner similar to that of the outer shell 14. Since duct 17 is not exposed to intense heat ordinary sheet metal 5 may be used for its construction.

A pair of wide fins 20 and 22 and a pair of smaller positioning fins 24 and 26 are secured to the combustion cylinder 12.

The free sides of the wide supporting fins 20 and 22 project into and are secured in the seams of the outer conical shell which is made in two half sections 16 and 18. The smaller positioning fins 24 and 26 contact the inner conical surface of outer shell 14 and serve as a guide to assure the correct spacing between the latter 15 and the combustion cylinder 12. These specific distances are explained in detail in copending application S. N. 179,710 referred to above.

The fins 20, 22, 24 and 26 have short legs 28, 30, 32 and 34 which project beyond and around the end of the 20 combustion cylinder 12. These legs 28, 30, 32 and 34 are secured to the sides of the cup shaped cap, preferably by welding or the use of hard solder so as to provide a minimum of interference with air entering between the annular opening between the cup shaped cap and the 25 combustion cylinder 12. It will thus be seen that I have provided a means for rigidly securing the cup shaped cap 10 and the combustion cylinder 12 so that the spacing between the two units is fixed and cannot be disturbed. It will be noted that this is one of the critical 30 portions of the jet burner and applicant has found that his present structure has enabled this critical spacing to be maintained so that the annular opening between these two elements is uniform around the entire circumference. The outer edges of the fins 20 and 22 are secured in 35 suitable off-set portions formed in the flanges 36 and 38 of the shell sections 16 and 18 of the shell 14 by suitable means such as spot welding or by bolts or rivets.

It will thus be seen that I have provided a simple 40 means for accurately mounting the combustion cylinder 12, the outer conical half shells 16 and 18, and the cup shaped cap 10 so that the critical spacings between these units are correctly made during assembly and cannot be readily disturbed in the field or in the process of shipping. It will further be noted that I have not interposed 45 any support in the annular opening which it has been found will interfere with a uniform continuous ribbon of air being discharged through the annular openings. Any interference with a continuous ribbon or stream of air such as is obtained in the present apparatus tends to permit carbon to accumulate on different portions of the combustion chamber. In other words I have found that the combustion chamber remains carbon free if the correct amount of air is introduced in the proper manner so that what appears to be a washing effect is obtained 50 on that portion of the combustion chamber which might otherwise tend to accumulate carbon.

The cup shaped cap 10 has a circular opening 40 formed in the center of its bottom portion. The spinner plate 42 is a stationary deflector provided with radial 55 louvers 44 and holes 46 formed near the inner edge of said louvers 44 to impart spinning motion to fluids passing over it. Attached to the spinner plate 42 are three 60 positioning brackets 48, 50 and 52. Each bracket has a spacing leg 55 which spaces the spinner plate the correct distance from the bottom of the cup shaped cap 10. Each leg has a short little lug 54, 56 and 58 which fits into a corresponding hole formed in the spinner plate 42 as shown in Fig. 2. The lug is flush with the upper 65 face of the spinner plate and may be held in position either by clinching or staking the end of the lugs 54, 56 and 58 when the lugs have been properly positioned in their respective holes in the spinner plate 42. It is also possible to employ welding or a hard solder for maintaining the lugs 54, 56 and 58 securely attached to 70 their respective holes formed in the spinner plate 42. The outside edges of the supporting brackets 48, 50 and 52 are designed to fit snugly into the hole 40 formed in the cap 10 to thereby center the spinning plate 42 with respect to the center opening 40 formed in the cap 10. 75 The brackets 48, 50 and 52 are secured to the cup shaped cap 10 by tack welding or other suitable means.

A short tube 60 fits snugly in between the inside edges of the brackets 48, 50 and 52 and is mounted flush with the bottom portion of the cup shaped cap 10. It is held in this position by tack welding the brackets 48, 50 and 52 to the tube 60.

A nozzle consisting of a stem 62, and a spray head 64 is inserted inside of the tube 60 to a position where the nozzle head is spaced from the edge of the center hole 66 formed in the spinner plate 42 a distance of $\frac{1}{64}$ of an inch with a tolerance of approximately plus or minus .005 of an inch. It has been found that this spacing permits the right amount of air to enter between the nozzle head 64 and the opening 66 of the spinner plate 42 so that there is no accumulation of carbon on the inside of the combustion cylinder 12.

The tube 60 has a slot 68 formed at one end and a conventional clamp 70 is tightened by means of screw 72 when the nozzle stem 62 has been inserted into the tube 60 to the position desired. Stem 62 is also provided with a threaded coupling 74 which engages with a conventional fitting 76, thus connecting the oil pressure line 78 to the coupling 74 and stem 62 which permits the oil to be delivered to the nozzle head 64.

I have shaped my cup-shaped cap 10 so that a curved contour is formed where the "Visa" flame tube 80 is connected to the cap so as to avoid the creation of unnecessary turbulences within the combustion chamber and therefore the accumulation of carbon is avoided. The "Visa" flame detector 82 is secured to the tube 80 by means of a conventional clamp screw 84.

A spark plug opening is also formed in the cup-shaped cap 10 in such a way that the entrance is curved and sharp edges have been avoided. A spark plug holder 86 is secured to the cap 10 by means of a conventional screw clamp 88. The spark plug holder 86 is formed with elongated slots or openings 90 which permit air to enter adjacent this point. The electrodes 92 and 94 of the spark plug 96 project inside of the combustion chamber to a distance where they are adjacent the fringe of the oil spray.

It will thus be seen that I have provided an improved structural arrangement for my jet tobacco curing burner which embodies all of the desirable features of my former application and at the same time has provided supports for three of the main principal elements of my invention, namely, the outer conical half shells 16 and 18, the cylindrical combustion chamber 12 and the cup shaped cap 10 which permit quick and accurate assembly of parts and also provides for the necessary sturdiness to provide satisfactory service in the field. For further information with respect to the distance said elements are spaced from one another, reference may be made to the application herein before referred to.

The spinner plate 42 has a cut away portion 98 which it has been found allows sufficient air to pass by the spark plug without detracting from the completeness of the fuel combustion. A special cut away portion is formed in that portion of the spinner plate which is immediately adjacent the electrodes of the spark plug.

It was found that carbon had a tendency to accumulate on the electrodes 92 and 94 of the spark plug in the burner as originally designed. Various efforts were made to correct this deficiency such as changing the length of the electrodes, forming holes in the spark plug, and changing the location of the spark plug. While these efforts had some success, I found that by cutting away a portion of the spinner plate 42 in the manner shown in Fig. 3, the accumulation of carbon on the spark plug was avoided. This is believed to have produced the desired turbulence of air so as to prevent carbon from having an opportunity to accumulate.

I have found that the burner herein works very well when fuel oil is fed into the burner at the rate of approximately two and a half gallons per hour, and air is forced into the burner at the rate of 100 to 125 cubic feet per minute. It is of course possible to deviate from these amounts and I have found that the burner will also operate with an air flow of 75 to 150 cubic feet of air per minute.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. In a jet burner, an outer air-conducting shell made in two longitudinal half-sections, an inner cylindrical combustion chamber shell and a cup having its open end shaped cap extending into one end of and of smaller diameter than the combustion chamber shell, spacing fins secured to the outside circumference of said inner combustion chamber shell, a leg formed on each of said fins and spaced from said cylindrical combustion chamber shell for spacing said cup shaped cap from said combustion chamber shell without interfering with the continuous annular flow of air through the opening between said cap and chamber, longitudinal outwardly extending flanges formed at the edges of the outer shell sections where said sections are joined together, off-set portions formed in said flanges for receiving the outer edges of said fins, and means for fixedly securing said flanges and outer edges together.
2. In a jet burner, an outer shell, an inner cylindrical combustion chamber shell, and a cup shaped cap having a concentric circular air inlet opening formed in the closed end thereof and having the open end extending into one end of and of smaller diameter than the combustion chamber shell, a spinner plate having perforations and louvers formed therein, L shaped supporting brackets supporting said spinner plate at a distance from said circular opening, the feet of said brackets being attached to and spacing the spinner plate from the inside of the cap and the legs of said brackets extending through said opening, a nozzle supporting tube connected to the inside of said legs, a nozzle stem adapted to fit inside of said tube and a clamp for holding said nozzle secure to the inside of said tube.
3. In a jet burner, an outer conical shell, an inner combustion cylinder shell and a cup shaped cap having an air inlet hole formed in the center thereof and having the open end extending into one end of and of smaller diameter than the combustion chamber shell, and a pair of holes formed in said cap in proximity to the center hole, a flame detector connected to one of said holes, a spark plug connected to the other of said holes, and a spinner plate spaced inwardly from and centered over the central hole formed in said cup shaped cap, said spinner plate having a cut-away portion adjacent to the position of the spark plug to cause incoming air from said air inlet hole to stream past the electrodes of the spark plug.
4. A jet type burner of the type having an outer shell, an inner shell spaced from the outer shell, a cup shaped cap spaced from and positioned at one end of said inner shell, said cup shaped cap having its open end extending into one end of and being of smaller diameter than the inner shell, said cup shaped cap having a circular air inlet opening formed in the center thereof, a spinner plate having perforations and louvers formed therein positioned inwardly of said circular opening, brackets fixedly attached to said spinner plate extending through the opening formed in said cup shaped cap for spacing said spinner plate a predetermined distance from said opening and being secured to said cup shaped cap, a nozzle supporting tube fixedly secured between said brackets, a nozzle, a clamp for fixedly holding said nozzle in said tube, openings formed in said cup shaped cap adjacent said circular opening, a spark plug mounted in one of said adjacent openings, and a flame detector mounted in another of said adjacent openings, the cap surfaces immediately adjacent the spark plug and flame detector openings being smooth and rounded to obtain a smooth flow of air from said air inlet opening and across the surface of the cup shaped cap.
5. In a jet burner, an outer shell, an inner combustion cylinder and a cup shaped cap having its open end mounted in one end of said inner combustion cylinder, said cup shaped member having a circular air inlet opening formed in the center thereof, a spinner plate having perforations and louvers formed therein positioned inwardly of said circular opening, a spark plug extending through said cup shaped cap at one side of said spinner plate, said spinner plate having a portion of its circumference adjacent the spark plug cut-away, brackets fixedly secured to said spinner plate extending through the opening formed in said cup shaped cap for spacing said spinner plate a predetermined distance from said opening, a weld fixedly securing each of said brackets to said cup shaped cap, a nozzle supporting tube fixedly se-

cured between said brackets, a nozzle, and a clamp for fixedly holding said nozzle in said tube.
